CLAIM

The ornamental design for a mining truck, as shown and described.

DESCRIPTION

The patent or application file contains a least one drawing executed in color. Copies of this patent or patent application publication with color drawing(s) will be provided by the Office upon request and payment of the necessary fee.

FIG. 1 is a front perspective view of a mining truck showing my new design in greyscale;

FIG. 2 is a rear perspective view thereof;

FIG. 3 is a side view thereof;

FIG. 4 is an opposite side view thereof;

FIG. 5 is a front view thereof;

FIG. 6 is a rear view thereof;

FIG. 7 is a top view thereof;

FIG. 8 is a front perspective view of a mining truck showing my new design in an alternate embodiment in color;

FIG. 9 is a rear perspective view thereof;

FIG. 10 is a side view thereof;

FIG. 11 is an opposite side view thereof;

FIG. 12 is a front view thereof;

FIG. 13 is a rear view thereof; and,

FIG. 14 is a top view thereof.
